(57) **CLAIM**

The ornamental design for a toy weapon, as shown and described.

DESCRIPTION

FIG. 1 is a front right side isometric view of a toy weapon in accordance with the new design;

FIG. 2 is a right side elevational view thereof;

FIG. 3 is a bottom plan view thereof;

FIG. 4 is a top plan view thereof;

FIG. 5 is a left side elevational view thereof;

FIG. 6 is a front elevational view thereof; and,

FIG. 7 is a rear elevational view thereof.

The broken lines shown in FIGS. 1-7 are for the purpose of illustrating portions of the toy weapon that form no part of the claimed design.
